UNITED STATES PATENT OFFICE.

WILLIAM R. WHITE, OF NEOGA, ILLINOIS.

SLIDING AND SWINGING GATE.

SPECIFICATION forming part of Letters Patent No. 252,343, dated January 17, 1882.

Application filed May 11, 1881. (Model.)

To all whom it may concern:

Be it known that I, WILLIAM R. WHITE, of Neoga, Cumberland county, Illinois, have invented an Improvement in Sliding and Swinging Gates, of which the following is the specification.

My invention is a gate constructed, as fully described hereinafter, so as to secure the requisite operations with little exertion by the operator, and by the use of simple appliances.

In the accompanying drawings the figure is a side elevation of my improved gate.

A A' are the gate-posts on either side of the roadway. D is a block of wood at the base of the post A. At the top of the post A is an arm, e, the projecting end of which is perforated, to receive a trunnion, a, on the upper end of a turn-post, h, the other end of said post h having a similar trunnion fitting a bearing in the block D, so that said post can be easily revolved. The post h is divided so as to receive between its sides a sliding gate, B. Through the post h passes transversely a shaft, b, carrying a grooved pulley, K, and provided with a crank-handle; and a bar, H, is secured to the turn-post h, constituting a rail on which rest rollers s s at the sides of the end bars of the gate, which gate may travel on the rail, as shown, a rope or chain, p, being fastened to

the gate at x x', and passing round the roller 30 K. When the crank is turned the roller turns with it, and thus causes the gate to travel through the turn-post, the heaviest gates being thus moved readily and easily. When the gate is moved away from the post A' the turn-post h and gate may be revolved to bring the gate at right angles to the position it first occupied, leaving the roadway clear.

A roller, d', may be placed in a bracket beneath the gate to support it at any point of 40 its length until it occupies a position central with the turn-post, when it will be away from the roller.

I claim—

The combination of the divided turn-post h, 45 supported adjacent to a post, A, with a gate, B, sliding between the sides of the post h, and provided with rollers s s, resting on a rail, H, secured to the turn-post, and a roller, K, on a crank-shaft, and cord p, all as set forth.

In testimony whereof I have signed my name to this specification in the presence of two subscribing witnesses.

WILLIAM RICHARD WHITE.
